UNITED STATES PATENT OFFICE

FRED BURCH, OF MILFORD, MICHIGAN, ASSIGNOR TO VAN DRESSER SPECIALTY CORPORATION, OF DETROIT, MICHIGAN, A CORPORATION OF MICHIGAN

POCKET AND METHOD OF FORMING THE SAME

Application filed May 30, 1930. Serial No. 457,633.

This invention relates to a pocket and to a method of forming the same and has particular reference to a pocket adapted to be associated with a panel and to a method of forming the pocket and applying the same to the panel.

One of the primary objects of this invention is to provide a pocket construction which will be neat in appearance and which will efficiently withstand the use to which it is subjected.

A further object of this invention is to provide a pocket construction and a method of forming the same, which method may be economically carried out on a commercial scale to produce an inexpensive construction.

Other objects and advantages of the invention, together with the numerous novel features thereof, will become more apparent as the following description proceeds, particularly when reference is had to the accompanying drawings wherein:

Figure 1 is an elevational view of a panel to which a pocket constructed in accordance with the teachings of this invention may be applied;

Figure 2 is a detail elevational view of one of the elements forming a part of the pocket construction;

Figures 3, 4 and 5 are elevational views showing successive steps in the method of making the pocket and of applying the same to the panel;

Figure 6 is an elevational view of a panel showing a pocket constructed in accordance with the teachings of this invention associated with the same;

Figure 7 is a sectional view taken substantially on the line 7-7 of Figure 6;

Figure 8 is an elevational view showing a step in a slightly modified method of producing a pocket;

Figure 9 is an elevational view of a panel showing a pocket constructed in accordance

with the teachings of the modified method associated with the same; and

Figure 10 is a detail perspective view of a portion of the structure shown in Figure 8.

As brought out before, the invention is directed to a pocket construction and to a method of forming the same and of mounting the pocket construction on a panel. The invention will find particular utility in connection with the mounting of a pocket on the door or like panel of an automobile and the invention will be so described, although it is to be clearly understood that the invention will find equal utility in mounting a pocket on a panel of any type whatever.

Referring then particularly to the drawings wherein like reference characters designate corresponding parts throughout all views, the numeral 15 designates a panel which, as illustrated, may be the door panel of an automobile. This panel, as is customary, is formed of cardboard or some similar material, and is covered with a suitable upholstery material, such as the cloth 16.

The method of forming a pocket and mounting the same on this door panel in accordance with the teachings of this invention consists in first forming a resilient frame of relatively heavy wire. This frame may be substantially U-shaped in elevation, being formed with the base 17 and the spaced sides or legs 18, the latter being formed at their free ends with the loops 19. A coil spring cable 20 is then connected to the loops 19 in the manner clearly illustrated in Figure 2 of the drawings.

The next step in the method consists in expanding the frame by moving the sides 18 away from each other to the position shown in Figure 3 of the drawings. This results in a stretching of the cable 20 and, while the latter is thus stretched, a cover 21, which has previously been formed by cutting the same from a piece of material similar to the cloth 16, is looped over the cable and stitched as

at 22 to form a hem 23 around the cable 20. As illustrated, the cover 21 is slightly larger than the frame when the latter is expanded so that when the frame returns to its normal 5 unexpanded position, the hem 23 will be shirred on the cable 20.

The frame is then placed on the panel 15 in the desired position and with the cover folded back in the manner illustrated in 10 Figure 4 of the drawings, U-shaped clips 25 are forced through the panel with the legs of the U-shaped clips straddling the wire forming the frame. The free ends of the U-shaped clips are then bent laterally to fix the 15 clips to the panel and to anchor the frame in its proper position.

With the frame fixed to the panel, the cloth cover is then folded down over the frame and the free edge of the cover is slit opposite 20 the clips 25 as indicated by the reference character 26. The free edge of the cover is then folded under and around the frame to enclose the same and the cover is then stitched to the panel 15 by a line of stitching 27 which, 25 as illustrated, is arranged immediately adjacent the frame. This line of stitching passes not only through two thicknesses of the cover member where the same is looped around the frame, but passes also through the 30 panel 15 and the cloth cover 16 thereof so that the cover 21, together with the frame, is fastened securely to the panel 15.

From the above it is believed that the structure of the pocket and the method of forming the same will be clearly apparent. The pocket proper, formed by the cloth piece 21 mounted on the frame, is fixed as a unit to the face of the panel 15. The cover 16 on the panel covers the inside of the pocket 40 while the cover 21 on the frame forms the outside of the pocket. The hem 23 at the top of the pocket provides the desired fullness to permit a stretching of the cable 20 incident to an opening of the pocket and the 45 frame provides not only a guide for the line of stitching 27 but provides also a reinforcing bead around the edge of the pocket which serves to prevent tearing of the edge of the pocket and also serves to improve to a considerable extent the appearance of the 50 pocket.

In Figures 8, 9 and 10 a slightly modified pocket construction and method of producing the same is disclosed. By reference to 55 these figures, it will be noted that there is first provided a panel 30 which may, in accordance with the usual practice, be formed of cardboard or the like. This panel is relatively small as compared to the door panel 60 31 and is provided with an upholstery cover 32 in accordance with the usual practice.

Fixed to the panel 30 by the tabs 33 and 65 clips 34 is a coil spring cable 35 over which a pocket cover 36 is looped and stitched, as indicated by the reference character 37, to

form a hem 38. The free edge 39 of the cover 36 is then stitched as at 40 to the panel 30, the line of stitching 40 defining the line of the pocket.

The door panel 31 is covered, in accordance 70 with the usual practice, with an upholstery cover 45 and this covered panel is blanked out, as indicated by the reference character 46, to produce an opening substantially the size and shape of the pocket desired. The 75 panel 31 is then placed over the panel 30 with the opening 46 opposite the pocket cover 36, the arrangement being such that the portion of the panel 31 surrounding the opening 46 conceals the line of stitching 40 80 and securing members 33 and 34 of the pocket construction. Thus, the opening 46 provides for access to the pocket in the manner clearly illustrated in Figure 9 of the drawings while the panel conceals the stitching 40 and the 85 selvage of the cloth cover 36.

The securing members 33 and 34 constitute an important feature of the last described form of construction and by reference to Figure 10 of the drawings, it will be noted 90 that the member 34 comprises a clip formed of a single piece of wire bent to form the leg 50 and the side 51 bent to extend at substantially right angles to this leg. The end 52 of the side 51 is returned bent as at 53 adjacent the top of the clip and lies adjacent the free end 54 of the side 55 of the clip which extends at an inclination from the leg 50. A tape 56 is looped around the leg 50 and this tape is adapted to be secured to 100 the panel 30 in any desired manner such, for example, as by the stud 57.

The free ends 52 and 54 of the piece of wire forming the clip provide a hook for engagement with the free end of the coil 105 spring cable 35 in the manner clearly illustrated in Figure 10 of the drawings, and being arranged adjacent the top of the clip, serve to maintain the coil spring cable adjacent the top of the pair of clips and therefore adjacent the top of the hem 38. The tape 56, when looped around the leg 50 of the clip, may be secured in place on the panel 30 either by the stud disclosed or by stitching, 115 if the latter is preferred.

From the above it is believed that the invention will be clearly apparent both as to the preferred and modified forms of construction. The invention provides a pocket which is simple in construction and which may be inexpensively produced and secured to the door or like panel of a motor vehicle. When the first described method is followed, the necessity of covering an auxiliary small 120 panel is eliminated while still providing for the covering of the inside and outside of the pocket with upholstery material. When the second described method is utilized, the invention provides for the firm attachment of 125 130

the ends of the coil spring cable to the panel to which the pocket is to be applied.

While the invention has been described with considerable detail, it will be readily apparent that various changes may be made in the details of construction and steps of the method without departing from the spirit of the invention. The right is therefore reserved to make such changes in the details of construction and steps of the method as will fall within the purview of the attached claims.

What I claim as my invention is:

1. A pocket construction including in combination, a panel, a frame having a base portion and spaced side portions, a resilient member connecting the free ends of the side portions of the frame, a cover having an upper hem portion shirred on said resilient member and having an edge portion folded around said frame, clips fixing said frame to said panel, and a line of stitching securing said cover to said panel adjacent said frame.

2. A pocket construction including in combination, a panel, a substantially U-shaped frame, a resilient member connecting the legs of said frame, a cover having a hem portion shirred on said resilient member and having an edge portion folded around said frame, securing members fixing said frame to said panel, and a line of stitching securing the edge of said cover around the frame and to the said panel.

3. In a pocket, a substantially rigid panel constituting the back wall of the pocket, a frame portion defining an edge of the pocket secured to the panel, and a cover for said frame forming the front wall of the pocket, said cover having an edge portion enclosing said frame portion.

4. In a pocket construction, a substantially rigid panel constituting the back wall of the pocket, a frame having a bottom portion and spaced side portions defining the bottom and side edges of the pocket, means securing said frame to the panel, and a cover for said frame forming the front wall of the pocket, said cover having an edge portion enclosing said frame.

5. In a pocket construction, a substantially rigid panel constituting the back wall of the pocket, a substantially U-shaped frame defining the side and bottom edges of the pocket, means securing said frame to the panel, and a cover for said frame forming the front wall of the pocket, said cover having a marginal portion enclosing said frame and secured thereto.

6. In a pocket construction, a substantially rigid panel constituting the back wall of the pocket, a frame having a base portion and spaced side portions defining the bottom and side edges of the pocket, said frame being secured to the panel, and a cover for said frame forming the front wall of the pocket, said

cover having an edge portion enclosing the said frame and secured thereto.

7. In a pocket construction, a substantially rigid panel constituting the back wall of the pocket, a frame having a base portion and spaced side portions defining the bottom and side edges of the pocket, means securing said frame to the panel, a resilient member connecting the free ends of the side portions of the frame, and a cover for said frame having an upper hem portion sleeved on said resilient member and having an edge portion enclosing said frame and secured thereto, said cover constituting the front wall of the pocket.

8. In a pocket construction, a substantially rigid panel constituting the back wall of the pocket, a frame defining an edge of the pocket, clips embracing said frame and secured to said panel for securing said frame to the panel, and a cover for said frame forming the front wall of the pocket, said cover having an edge portion enclosing said frame and secured thereto.

9. In a pocket construction, a substantially rigid panel constituting the back wall of the pocket, a frame defining an edge of the pocket, said frame having spaced side portions, means securing said frame to said panel, a resilient member connecting the said spaced side portions of the frame, and a cover for said frame forming the front wall of the pocket, said cover having an upper hem portion sleeved on said resilient member and having a marginal hem portion enclosing said frame.

10. In a pocket construction, a substantially rigid panel constituting the back wall of the pocket, a frame portion defining an edge of the pocket secured to the panel, a cover for said frame forming the front wall of the pocket, said cover having an edge portion enclosing said frame portion, and a line of stitching securing the edge portion of said cover to said panel adjacent said frame portion.

11. In a pocket construction, a substantially rigid panel constituting the back wall of the pocket, a frame having a base portion and spaced side portions defining the bottom and side edges of the pocket secured to the panel, a cover for said frame forming the front wall of the pocket, said cover having an edge portion enclosing said frame, and a line of stitching securing the cover to the panel adjacent the said frame.

12. In a patch pocket construction, a substantially rigid panel constituting the back wall of the pocket, a strip member of appreciable thickness secured to the panel and defining the side and bottom edges of the pocket, and a patch of material constituting the front wall of the pocket, said patch of material having a marginal portion enclosing said strip member throughout the length thereof and secured thereto.

13. In a patch pocket construction, a substantially rigid panel constituting the back wall of the pocket, a frame defining the side and bottom edges of said pocket secured to said panel, a resilient member connecting the free ends of the portions of said frame defining the sides of said pocket, and a patch of material constituting a cover for said frame and the front wall of said pocket, said patch of material having an upper hem portion sleeved on said resilient member and having a marginal portion anchored to said frame throughout the length thereof.

In testimony whereof I affix my signature.

FRED BURCH.
